United States Patent Office

Des. 186,190
Patented Sept. 22, 1959

186,190

PEDAL GUITAR

Clarence L. Fender, Fullerton, Calif.

Application August 20, 1958, Serial No. 52,317

Term of patent 14 years

(Cl. D56—1)

I claim:

The ornamental design for a pedal guitar, substantially as shown.
